(57) **CLAIM**

The ornamental design for a surface neuro probe as shown and described.

DESCRIPTION

The file of this patent contains at least one photograph executed in color. Copies of this patent with color photographs will be provided by the Office upon request and payment of the necessary fee.

FIG. 1 is a front view of a surface neuro probe showing my new design;

FIG. 2 is a right side view thereof;

FIG. 3 is a left side view thereof;

FIG. 4 is a rear view thereof;

FIG. 5 is a top view thereof;

FIG. 6 is a bottom view thereof;

FIG. 7 is a bottom left and front perspective view thereof;

FIG. 8 is another bottom left and front perspective view thereof;

FIG. 9 is a left side perspective view thereof; and,

FIG. 10 is a left top perspective view thereof.
